(57) **CLAIM**

The ornamental design for a volumetric downlight light fixture, as shown and described.

DESCRIPTION

FIG. 1 is a perspective view of a volumetric downlight light fixture of the present invention, showing the fixture mounted therein a ceiling tile; and,

FIG. 2 is a bottom plan view of the volumetric downlight light fixture of FIG. 1.

The broken line showing of a ceiling tile is included for the purpose of illustrating environmental structure and forms no part of the claimed design.
